(Cl. D93—4)

To all whom it may concern:

Be it known that we, Walter Lausman and Oliver R. Siewert, both citizens of the United States of America, residing at Baroda, in the county of Berrien, State of Michigan, and at St. Joseph, in the county of Berrien, State of Michigan, respectively, have invented a new, original, and ornamental Design for a Puttying Tool, of which the following is a specification, reference being had to the accompanying drawing, forming part hereof.

Fig. 1 is a top plan view of a puttying tool embodying our new design;

Fig. 2 is a view thereof in end elevation;

Fig. 3 is a view thereof in rear elevation;
Fig. 4 is a view thereof in front elevation; and
Fig. 5 is a view thereof in bottom plan.

We claim:

The ornamental design for a puttying tool, substantially as shown.

WALTER LAUSMAN.
OLIVER R. SIEWERT.
